UNITED STATES PATENT OFFICE.

JOSEF SCHÄFER, OF DORTMUND, GERMANY.

DEVICE FOR CLOSING BOTTOM DOORS OF VERTICAL COOKING CHAMBERS OR VERTICAL RETORTS IN COKE OVENS AND THE LIKE.

Application filed November 11, 1920. Serial No. 423,479.

To all whom it may concern:

Be it known that I, JOSEF SCHÄFER, a citizen of Germany, and a resident of Dortmund, in the Republic of Prussia, Germany, have invented certain new and useful Improvements in Devices for Closing Bottom Doors of Vertical Coking Chambers or Vertical Retorts in Coke Ovens and the like, of which the following is a specification.

10 In vertical coking-chambers or vertical retorts, as employed in the manufacture of gas, the bottom-doors are usually closed by hand after the coke has been delivered into the coke-quenching-wagon. This operation 15 is, however, incommodious and unhealthy on account of the development of gases and of the influence of the heat. To avoid these drawbacks and to close the bottom-doors of the coking-chambers conveniently and as 20 quickly as possible, separately operative mechanical lifting-devices have hitherto been employed, but for all that it was an absolute necessity to perfect the closing of said doors by means of a final and dextrous 25 use of the hand.

This inconvenience I avoid by means of my present invention, according to which the coke-quenching-wagon is provided with a standard projecting over the normal-projectile of said wagon to such an extent that on starting this wagon after having received the contents of a coking-chamber, said standard will strike against a projecting member of said bottom-door and swing it 35 into its closing-position wherein it is automatically locked. To accomplish this with ease said member of the bottom-door is provided with a pressure-roller adapted to contact with an upwardly and rearwardly projecting contact-arm of said standard, which 40 is slidingly arranged at the rear-end of said wagon and yieldingly supported thereon by a spring in the direction of pressure.

In the accompanying drawing my present invention is illustrated by way of example as applied to a vertical coking-chamber of a coke-oven.

The discharge-opening of the vertical coking-chamber or retort 1 is faced by a rigid frame 2 which simultaneously serves as a seat for the bottom-door 3 hinged to a bracket 4. The latter is shown as bolted to an adjacent I-beam 5, but might, of course, form an integral part of said frame 2, if so desired. When the newly produced coke is

ready to be withdrawn from the coking-chamber or retort the coke-quenching-wagon 6 is pushed beneath it and then the locking-cam 7 retaining said bottom-door in its closing-position is retracted by rotating the counter-weighted shaft 8. The bottom-door thus released will swing downward into its hanging position (indicated by dotted lines) whereas the glowing coke, now deprived of its support, will drop into the coke-quenching-wagon. On starting and moving the wagon forward the bottom-door 3 must be closed, which is accomplished by means of my present invention automatically in the following manner:

At the rear-end of the coke-quenching-wagon 6 brackets 9 are provided for the reception of a standard 10 terminating in an upwardly and rearwardly inclined contact-arm 11 strengthened by a diagonally arranged brace 12. The standard 10 is vertically supported by a spring 13 mounted upon an extension 14 of the wagon-frame 15. This spring is provided to allow the standard to yield when it encounters a greater resistance than the determinable pressure required to simply raise the bottom-door to its seat. After the wagon has been started the pressure-roller 16, journalled in a bracket 17 of the bottom-door 3, comes into contact 85 with the standard 10 at the base of the knee 18, whereupon the bottom-door will be swung toward the right and simultaneously elevated. The roller 16 will hereby ride upon the top-face of the contact-arm 11 until the bottom-door comes into contact with its seat 19 on the frame 2. Hitherto the resistance of the spring 13 was sufficient to support the standard in its elevated position but at this moment said standard will commence to be gradually pressed downward until the roller 16 has reached the highest point 20 of the contact-arm 11 (see dotted outline of the upper portion of said standard). During the latter part of the upward 90 movement of the bottom-door 3 the nose 21 of the latter pushed the locking-cam 7 aside whereby the counter-weight 22 in consequence thereof was swung to the left by means of the rock-shaft 8 carrying it. But 105 at the moment the nose 21 slides over the top-point 23 of the locking-cam 7 the counter-weight 22 will return this locking-cam to its normal position in which it is enabled to retain the bottom-door closed against the 110

weight of the full charge of the coking-chamber. Thus the locking-cam 7 attains its locking-position at about the time the roller 16 reaches the highest point 20 of the contact-arm 11, so that at the moment when said roller finally leaves said contact-arm, the bottom-door is securely locked and will be retained in this position by the locking-cam 7 until the latter is intentionally retracted by rotating the shaft 8 anew. It will be observed that the upper-face 24 of the contact-arm 11 is shaped in such a manner that at any time during the closing operation of the bottom-door that part of said arm 11 in effective contact with the pressure-roller will form at the point of contact a tangent to this roller and thus insure a quick and reliable closing of said bottom-door.

I claim:

- 20 1. A device of the character described comprising in combination with a coke-quenching-wagon and the bottom-door of a vertical coking-chamber, a standard mounted vertically movable on said wagon and projecting over the normal-profile of the latter, a pressure-roller carried by said bottom-door, an inclined contact-arm carried by said standard and adapted to cooperate with said roller for closing said bottom-door when said wagon is set in motion after having received the coked contents of said coking-chamber, and locking-means mounted adjacent said bottom-door and adapted to be pushed out of its locking-position by said door while ascending, but to lock said door automatically after being closed by said contact-arm; substantially as set forth.
- 30 2. A device of the character described, comprising in combination with a coke-quenching-wagon and the bottom-door of a vertical-coking-chamber, a standard pro-

jecting over said wagon, means on said wagon for slidingly retaining said standard in a vertical position, a yielding member sustaining said standard on said wagon and adapted to permit a depression of said standard when encountering undue resistance, a contact-roller mounted on said bottom-door, an upwardly and rearwardly inclined contact-arm on said standard adapted to operate said pressure-roller for closing said bottom-door when said wagon is advanced after having received the coked contents of said coking-chamber; an oscillating locking-means journaled adjacent said bottom-door and adapted to be swung out of its locking-position by said door when ascending and to return automatically into its locking-position while said bottom-door is still being pressed against its seat, substantially as set forth.

3. A device of the character described, comprising in combination with a coke-quenching-wagon and the bottom-door of a vertical coking-chamber, a standard mounted on said wagon to yield in a vertical direction of the pressure, a spring arranged on said wagon and sustaining said standard, a pressure roller carried by said bottom-door, an inclined contact-arm carried by said standard and adapted to always present a tangential contacting element to said roller during the closing-operation of said bottom-door, and means for automatically locking said bottom-door while still being pressed against its seat, substantially as set forth.

Signed by me at Dortmund, Germany, this 8th day of October, 1920.

JOSEF SCHÄFER.
